[57] CLAIM

The ornamental design for a can-shaped tool box, as shown and described.

DESCRIPTION

FIG. 1 is a perspective view of a can-shaped tool box showing my new design;

FIG. 2 is a right elevational side view thereof.

FIG. 3 is a left elevational side view thereof.

FIG. 4 is a top plan view thereof.

FIG. 5 is a bottom plan view thereof.

FIG. 6 is a rear view thereof.

FIG. 7 is a front view thereof; and,

FIG. 8 is a partially fragmentary front elevational view thereof, wherein the dotted line showing of the hang tag is for illustrative purpose only and forms no part of the claimed design.
